Inventor
J. T. Beam.

By Watson E. Coleman,
Attorney

UNITED STATES PATENT OFFICE.

JOHN T. BEAM, OF SULPHUR, OKLAHOMA.

TONGS.

Application filed August 9, 1922. Serial No. 580,700.

To all whom it may concern:

Be it known that I, JOHN T. BEAM, a citizen of the United States, residing at Sulphur, in the county of Murray and State of Oklahoma, have invented certain new and useful Improvements in Tongs, of which the following is a specification, reference being had to the accompanying drawings.

This invention relates to certain improvements in tongs and it is an object of the invention to provide a novel and improved device of this general character embodying means whereby the load lifted by the tongs may be weighed together with means to render the weighing mechanism inoperative.

Another object of the invention is to provide a novel and improved device of this general character embodying a hollow or tubular body through which extends a spring controlled rod provided with a handle wherein is employed a removable cap to facilitate the removal and application of the rod and particularly to facilitate the requisite adjustment of the spring associated with the rod.

The invention consists in the details of construction and in the combination and arrangement of the several parts of my improved tongs whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating tongs constructed in accordance with an embodiment of my invention, a second position of certain of the parts being indicated by dotted lines;

Figure 2 is a fragmentary view partly in section and partly in elevation of the device as herein disclosed, a second position of the rod or shaft being indicated by dotted lines;

Figure 3 is an elevational view of the rod or shaft and the parts carried thereby unapplied;

Figure 4 is a view in perspective of the upper or outer end portion of the body or

cylinder and a removable body associated therewith as herein comprised;

Figure 5 is a sectional view taken substantially on the line 5—5 of Figure 2; and

Figure 6 is a sectional view taken substantially on the line 6—6 of Figure 2.

As disclosed in the accompanying drawings, 1 denotes an elongated hollow or tubular body or cylinder, the inner or lower end of which being closed by the head or cap 2. The body or cylinder 1 is provided with a flattened face *a* which has disposed therewith at the transverse center thereof a slot 3. The face *a*, or more particularly the portions thereof at opposite sides of the slot 3 are held in fixed position by the cap 2 and by the cross strip 4 arranged at the upper or outer end of the body or cylinder 1.

The upper or outer end of the body or cylinder 1 is closed by the cap 6 which, when in applied position, has freely disposed therethrough the outstanding ears 7 carried by the walls of the body or cylinder 1 and each of which being adapted to have associated therewith a cotter pin 8 or other kindred member whereby the cap 6 is effectively maintained in applied position yet being capable of readily and conveniently being removed when the necessities of practice may require.

The cap 6 is provided with an opening or slot 9 through which is snugly extended an elongated rod 10 preferably flattened and which has its inserted extremity 10^a reduced in width and slightly increased in thickness with the edges of said portion 10^a threaded as at 11 to accommodate the nut 12.

The portion 10^a of the rod 10 is also directed through a plate or washer 14 positioned inwardly of the nut 12, which is provided with a straight edge *b* positioned adjacent the straight face *a* of the body or cylinder 1 and the central portion of said straight edge *b* is provided with an outstanding tongue or lip 15 of a length to extend through the slot 3, this tongue or lip 15 serving as a pointer or index for co-action with weight graduations 16 provided on the face *a* of the body or cylinder 1 and herein disclosed as arranged to one side of the slot 3.

Arranged within the body or cylinder 1 and surrounding the rod 10 is a coil spring

17 which is interposed between the plate or washer 14 and the plate 18 carried by the inner end of the sleeve or cuff 19. To the rod 10 is snugly disposed said sleeve or cuff 19, being in contact under the influence of the spring 17 with the applied cap 6. The tension of the spring 17 is under control of the nut 12. In order to effect such adjustment as the occasions of practice may necessitate the cap 6 is removed whereupon the rod 10 and the parts associated therewith may be readily removed from within the body or casing 1 when applied thereto. The outer or extended end portion of the rod 10 has engaged therewith a handle member or hand grasp 20.

Mounted upon the body or cylinder 1 for movement lengthwise thereof is a slide 21 provided with oppositely disposed outstanding ears 22 which is pivotally engaged as at 23 to the inner extremities of the tongs 24. The tongs 24 are of suitable dimensions and configurations and are of a type particularly adapted to grapple ice and other articles to be weighed. The links 25 operatively connect intermediate portions of the tongs 24 and the lower portion of the body or cylinder 1, the inner portions of said tongs 25 being herein disclosed as pivotally connected by the common pintle 26 to the outstanding wing or flange 27 carried by the cap 2.

Movement of the slide 21 inwardly of the body or cylinder 1 is limited by the outstanding stop members 28 carried by said body or cylinder 1 and inward movement of the slide 21 may be effected by engagement of a digit of a hand with the finger piece 29 herein disclosed as pivotally engaged with one of the clips 22. This finger piece 29 also provides means whereby the digit of a hand engaged with the handle member or hand grasp 20 may be employed to maintain the tong 24 in separated relation as illustrated in Figure 1.

With the tongs 24 engaged with a load a lifting movement effected by requisite pull upon the handle member or hand grasp 20 will cause the desired endwise relative movement between the rod 10 and the body or cylinder 1, resulting in the index or pointer 15 co-acting with the graduations 16 to readily determine the weight of such load.

In lifting articles of unusual bulk or weight such as large pieces of ice, box goods, etc., it is essential that the weighing mechanism be rendered inoperative as the weight of such heavy articles have a tendency to interfere with and injure such mechanism.

As herein disclosed, the outer or upper end portion of the body or cylinder 11 has threaded therethrough the clamping bolt 30 which, upon being urged in one direction passes through an opening 31 provided in a wall of the cuff or sleeve 19 and engages

within a recess or cavity 32 produced in a side casing of the rod 10 and whereby said rod 10 and the body or cylinder 1 are effectively locked against relative or independent movement.

From the foregoing description it is thought to be obvious that a tong constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

What is claimed is:—

1. A device of the class described comprising a scale including a body, a rod passing within the body and provided with a handle, tensioning means associated with the rod and body tongs slidably and pivotally connected to the body, links connecting the tongs to the body, and means for locking the rod against movement.

2. A device of the class described comprising a scale including a body, a rod passing within the body and provided with a handle, tensioning means associated with the rod and body, tongs slidably and pivotally connected to the body, links connecting the tongs to the body, and means carried by the body and engaging the rod for holding the rod against movement independently of the body.

3. A device of the class described comprising a body, a rod insertable within the body through an end thereof, a cuff within the body through which the rod extends, a stop member carried by the inserted end of the rod, a spring encircling the rod and interposed between the stop and cuff, and grappling means carried by the body.

4. A device of the class described comprising a body, a rod insertable within the body through an end thereof, a cuff within the body through which the rod extends, a stop member carried by the inserted end of the rod, a spring encircling the rod and interposed between the stop and cuff, grappling means carried by the body, said cuff being provided with an opening, and a member threaded through a wall of the body, said member being adapted to extend through the opening in the cuff and engage the rod to hold the rod against movement independently of the body.

5. A device of the class described comprising a tubular member having one end open, grappling means associated with the body, a cap for the open end of the body,

5 said cap being provided with openings, outstanding ears carried by the open end portion of the body and extending through certain of the openings in the cap, means insertable through the ears for holding the cap in applied position, a rod slidably extending within the body through another opening in the cap, and tensioning means associated with said rod and body.

10 6. A device of the class described comprising a scale including a body, a rod passing within the body and provided with a handle, tensioning means associated with the rod and body, tongs slidably and pivotally connected to the body, links connecting the tongs to the body, and means for limiting sliding movement of the tongs inwardly of the body.

15 7. A device of the class described comprising a scale including a body, a rod passing within the body and provided with a

20 handle, tensioning means associated with the rod and body, tongs slidably and pivotally connected to the body, links connecting the tongs to the body, and outstanding members carried by the body for limiting sliding movement of the tongs inwardly of the body.

25 8. A device of the class described comprising a scale including a body, a rod passing within the body and provided with a handle, tensioning means associated with the rod and body, tongs slidably and pivotally connected to the body, links connecting the tongs to the body, and means associated with the tongs and engageable by the digit 30 of a hand grasping the handle for holding the tongs against sliding movement relative to the body.

35 In testimony whereof I hereunto affix my signature.

JOHN T. BEAM.
